UNITED STATES PATENT OFFICE

LOUISE CROSS, OF NEW YORK, N. Y., ASSIGNOR TO FRANKART, INC., OF NEW YORK, N. Y.,
A CORPORATION OF NEW YORK

DESIGN FOR A STATUETTE FOR BOOK END, ASH TRAY OR SIMILAR ARTICLE

Application filed October 1, 1931. Serial No. 41,284. Term of patent 3½ years.

To all whom it may concern:

Be it known that LOUISE CROSS, a citizen of the United States and resident of New York city, in the county of New York and State of New York, has invented a new, original, and ornamental Design for Statuette for Book End, Ash Tray or Similar Article, of which the following is a specification, reference being had to the accompanying drawing, forming part thereof, in which,

The figure is a perspective view of a Statuette for book end or ash tray, embodying my new design.

I claim:

The ornamental design for a statuette for book end, ash tray or similar article, substantially as shown.

Dated, September 14, 1931.

LOUISE CROSS.
